HYDRAULIC JACK FOR PRESTRESSING CONCRETE

James W. Howlett, Oakland, Calif., assignor to
Howlett Machine Works

Filed July 6, 1971, Ser. No. 160,255

Term of patent 14 years

Int. Cl. D15—04

U.S. Cl. D41—3

Fig. 3

Fig. 4

Fig. 5Fig. 6

FIG. 1 is a side elevational view of a hydraulic jack for prestressing concrete constructed in accordance with my ornamental design with the phantom lines for the spring element being for convenience of illustration;

FIG. 2 is a top plan view thereof;

FIG. 3 is a side elevational view taken from the side opposite to the side illustrated in FIG. 1;

FIG. 4 is a bottom plan view thereof;

FIG. 5 is an end elevational view taken from the front end thereof; and

FIG. 6 is an end elevational view taken from the rear end thereof.

I claim:

The ornamental design for a hydraulic jack for prestressing concrete, as shown and described.
